TIME RECORDING DEVICE

George R. Wood, Toronto, Ontario, Canada, and
Edward J. Von Pein, Dayton, Ohio, assignors
to International Business Machines Corp., New
York, N. Y., a corporation of New York

Application July 10, 1935, Serial No. 30,588

3 Claims. (Cl. 101—287)

This invention relates to time recording devices and more particularly to new and improved time recorders in which the operator signs his autograph at the time he registers beside the record of the time which is made when he effects 5 said registration.

It has for its object the provision of a new and simplified construction which may be more readily and easily manufactured than those heretofore known in the art.

Various other objects and advantages of our invention will be obvious from the following particular description of one form of mechanism embodying the invention or from an inspection 15 of the accompanying drawings; and the invention also constitutes certain new and novel features of the construction and combination of parts hereinafter set forth and claimed.

In the drawings:

20 Fig. 1 is a plan view of the device with casing removed.

Fig. 2 is an elevational section taken through lines 2—2 of Fig. 1.

Fig. 3 is a side elevation taken along lines 3—3 25 of Fig. 1.

Fig. 4 is a cross section taken through line 4—4 of Fig. 1.

Fig. 5 is a perspective drawing of the complete 30 device with the casing in place.

The base 10 of suitable material may be provided having struck down portions 11 integral with said base for supporting the base and provided with side plates 12 and 13 rigidly fixed to the base by studs and lock nuts fastened to ears 35 14 integral with the side plates. The top edges of the plates are held rigidly by a plate 15 which is likewise fastened to ears integral with the side plate, and have a portion of said plate turned upwardly as shown at 15' (Fig. 3).

40 Time unit

The side plate 12 has mounted thereon a suitable constant speed electric motor 16 fastened thereto by bolts 17 and held out from the side 45 of said plate by spacers 18. The shaft 19 of the motor has fixed thereto a cam 20 which makes one revolution per minute and which cooperates with a cam wiper 21 pivotally mounted on a stud 22 fixed to the side plate 12. Said cam wiper is 50 rigidly attached to a pawl arm 23 by means of a rivet 24, said pawl arm being pivoted on said stud 22 and biased in a counterclockwise direction by a spring 25. The pawl arm 23 carries a pawl 26 pivotally mounted thereon and biased in 55 a counterclockwise direction by a spring 27 to

cooperate with a ratchet wheel 28 which is pivotally mounted on a stud 29 fixed to the side frame. The ratchet wheel is fixed to a unit printing wheel 30 which carries the unit designation of the minute. A plurality of printing 5 wheels are provided as indicated at 31 (Fig. 1), each having a cooperating ratchet wheel and pawl for actuating the same. These wheels constitute the day wheel, the hour wheel, the tens 10 of minutes wheel and the units of minutes wheel.

The carry-over or transfer mechanism from the units to the tens minute and to the hour minute as well as from the hour to the day type wheel is accomplished in the well known manner, fully described in numerous patent disclosures such as, for example, Patent No. 771,494 by storing energy in a spring-biased pawl by means of a cam rotated integrally with the type member of a lower order so that the pawl drops from the cam at each revolution of the type wheel of the lower order to release the pawl and move the type wheel of the next higher order forward one step. As this method is old and well known in the art and plays no part 15 in the present invention, it is deemed that no further explanation of the transfer mechanism 20 is necessary.

An endless ribbon 32 is provided which is carried across the face of the type wheels and 25 around the timing unit on rollers 33, said rollers being supported by studs 34 fixed to the side frame. A driving roller 35 also pivotally mounted to the side frame is provided with suitable absorbent material which may be impregnated with 30 ink to keep the ribbon constantly supplied. This driving roller has fixed to it a ratchet wheel 36 (Fig. 3) cooperating with a pawl member for feeding the ribbon in a manner to be described later. The ribbon is held under suitable tension 35 by a roller 37 pivotally mounted on a lever 38 which in turn is pivotally supported on the stud 39 and biased in a clockwise direction by the spring 40 fixed to the side frame.

A printing hammer 41, provided with a platen 45 45, is pivoted on a stud 43 and is biased in a counterclockwise direction by a spring 44 fastened at one end to a projection 45 integral with a printing hammer and a projection 46 integral with a bracket 47 pivoted on said stud, said 50 bracket spanning the printing hammer and provided with a cross member 48 (Fig. 1) which acts as a limit stop against further rotation of the printing hammer in a counterclockwise direction under the biasing action of the spring 44. The 55 bracket 47 has affixed to one end thereof a pro-

- jection 49 which cooperates with a hook 50 of an actuating member 51 pivoted on a stud 52 fixed to a registering lever 53 and biased by a spring to hold the hook 54 in cooperation with the projection 49. The upper end of the actuating member 51 is supplied with a cam-shaped surface 55 which cooperates with an eccentric bushing 56 so that when the member 51 is moved upwardly against this bushing, it will cam said member in a clockwise direction until the hook 50 is moved out of cooperation with the projection 49 to release the printing hammer to effect a printing operation, said printing hammer having in the meantime been moved in a counterclockwise direction as viewed in Fig. 2 by the upward movement of the hooked member 49 moving the bracket 47 in a counterclockwise direction. The bracket 47 when released is propelled clockwise by the spring 57, fixed to a stud 58.
- 20 The registration lever is pivoted to the side frame by means of a stud 59 and is biased in a counterclockwise direction by a spring 60 fixed to the projection 61 integral with said lever and the side frame (Fig. 3). The projection has 25 pivoted thereto a pawl member 62 biased downwardly by a spring 63 into cooperation with the ratchet wheel 36 fixed to the ribbon feed roller. A guide plate 64 fixed to the side frame holds said pawl into cooperation with said ratchet 30 wheel. When the registration arm is moved in a clockwise direction to effect registration, the link is moved to the left as viewed in Fig. 3 and catches the next tooth of the ratchet wheel so that upon its return motion the ribbon is fed 35 slightly past to present a fresher surface for subsequent registration. A guide member 65 spaced slightly outwardly from the side frame 12 is provided to hold the registration lever in proper alignment adjacent said side frame and an eccentric bushing 66 is provided as a limit stop for 40 limiting the upward movement of the registration arm and an eccentric bushing 67 is provided as a limit stop for the downward movement of the registration arm.
- 45 A U-shaped plate 68 is provided with extensions 69 that fit through slotted apertures 70 along the upper edge of the side frames to permit said plate to be slid backwards and forwards longitudinally of said side frame (Figs. 2, 3 and 4). Two levers 71 and 72 are fixed to a shaft 73 which is journaled in the side frames. Said levers are biased by a spring 74, one end of which is fixed to the lever 72 and the other end of which is fixed to a lever 75 which is pivotally mounted on said rod. 50 An extension 76 of the lever 72 rests against a stud 77 fixed to the lever 75 which acts as a limit stop for the relative movement between the levers 72 and 75 under the biasing action of said spring. The upper end of the levers 71 and 72 engage apertures 78 in the plate 68 (Fig. 1) so that when they are oscillated about their pivotal support, said plate is slid backward and forward.
- 55 The stud 77 projects through an aperture 108 in the side plate 12 and into the plane of movement of the registration lever 53. A slotted link 109 is pivotally mounted on the stud 77 and is provided with an elongated slot 110 which is slidably connected to a stud 111 fixed to the registration lever 53. When the registration lever is 60 depressed to make a printing registration the stud slides along the slot until it reaches the bottom, then upon further depression of the registration lever it pushes the link 109 downward to effect a paper feeding operation.
- 65 Four studs 79 are fixed to the U-shaped plate

and extend upwardly through cut-away portions in the plate 15 extending beyond the plane of said plate and have fixed thereto at their upper ends a plate 80 which moves backward and forward with the U-shaped plate.

5

The U-shaped plate pivotally supports two cam-shaped gripper members 81 which are biased by springs 82 to hold these members against the plate 80, said members extending through apertures 83 in the fixed plate 15. A third gripper member 84 is pivotally mounted on a struck-down portion 85 of the fixed plate 15 and is likewise biased by a spring 86 fastened to a bracket 87 formed integral with the plate 15. This gripper member is identical with members 80 and 81 and the cam surface makes contact with sunken surface 88 formed in a bracket 89 which is fixed to the side plates 12 and 13 and lies over and adjacent to the movable plate 80. The sunken or struck-down portion 88 projects through an aperture 90 of the movable plate 80 to provide a fixed surface against which the gripper 84 may grip the paper strip, the same as between the grippers 81 and the movable plate 80. A large spindle 91 is fixed to the side frame member 12 25 and is adapted to rotatably support a paper supply roll 92 which may be held on the spindle and in alignment by any suitable method. The paper from the supply roll indicated at 92 is passed in front of the ribbon and type wheels and is separated from the ribbon by a ribbon shield 93 fixed to the side frame and passes over roller 94 fixed to the side frame and under a gate 95 pivotally mounted on the sliding plate and from there the paper extends between the gripper members 80 and 84 and their coating plates and from thence extends out beyond the end of the plate where it is free to accumulate in the open space provided between the frame members as shown in Fig. 2.

40

The gate 95 is provided with an aperture 96 which renders the various recordings visible through a window 97 in the casing 98 and the transverse edge of the gate opposite the hinged edge acts as a shutter to cover the paper which is normally adjacent an aperture 99 in the covering case. The covering case 98 is provided with apertures at the lower rear end which are adapted to receive extensions 100 fixed to the base to hold it in position at its rear edge (Figs. 50 1 and 2) and which is provided with a bracket 101 and a hook locking member 102 which enter apertures 103 and 104 respectively in the base. The locking member is pivoted to the case and is adapted to be hooked onto the base. A lock 55 105 is mounted on the bracket 101 and is adapted to have its bolt moved adjacent the hook member by a key to prevent the member from being oscillated or unhooked from the base and thereby preventing the removal of the covering case. 60 The hooked member 102 is provided with a handle 106 extending through the front wall of the cover to manually swing the hooked member out of locking position with the base when it is desired to remove the cover.

65

When a registration is to be made, the person making such registration depresses the registration handle which extends through an aperture beyond the end of the case and by means of the hook member on the end of the registration lever, as previously described, operates the printing hammer to effect a printing operation, giving the day and time.

70

Upon further depression of the registration handle, the link 109 is moved downwardly as 75

previously explained carrying the stud 11 downwardly and thus rotating the arm 15 to oscillate the levers 11 and 12, as previously described. This causes the plates 68 and 80 to be slid toward the operator and the camming action of the grippers grips the paper strip and moves it with the sliding plate. The sliding action of this plate removes the upper end of the gate 95, which has been previously termed a shutter, from in front of the aperture 99 and brings the printed registration that has previously been made in the first part of the same operation into view whereby the operator signs his name adjacent the recorded time and enters a check in the column designated "In" or "Out" in accordance with the operation he is making, namely, whether he is registering on entering the place of business or registering on leaving the place of business. A name plate 107 is fixed to the casing 98 adjacent the aperture where the operator signs indicating the purposes of the various columns on the tape. When the registration is completed and the handle is released, it returns to its normal position and the shutter is moved back to cover the aperture, thus preventing any disfiguration of the record by an operator who may come to register subsequently. On the return motion of the sliding plate and the shutter, the gripper 94 holds the paper from any retrograde movement backward with said shutter.

The purpose of the glass is to show the time and the name of registration that have recently and previously been made in order to permit anyone who may be interested to observe the time of departure or arrival of operators. As an example, should a person be out for his lunch period and should this person be asked for in connection with business or personal matters, it is a simple matter to glance at the machine and note what time this person registered out and knowing the length of the lunch hour allowed, an accurate estimate of when that person is expected back can be given.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a time recorder, a continuous record strip, type wheels and a movable platen for printing a record on said strip, an actuating arm for operating said platen to effect a printing operation on said record strip, means operated by said actuating arm after the printing operation for moving said record strip, said means including a U-shaped plate member and a flat plate member disposed on opposite sides of the record sheet, 10 arcuate eccentric members carried by said U-shaped plate and adapted to grip the record strip between said arcuate members and said flat plate member when said members are moved in the direction in which the record strip is to be 15 fed.

2. In a time recorder, a continuous record strip, type wheels and a movable platen for printing a record on said strip, an actuating arm for operating said platen to effect a printing operation on said record strip, means operated by said actuating arm after the printing operation for moving said record strip, said means including a U-shaped plate member and a flat plate member disposed on opposite sides of the record sheet, 20 arcuate eccentric members carried by said U-shaped plate and adapted to grip the record strip between said arcuate members and said flat plate member when said members are moved in the direction in which the record strip is to be 25 fed and a shutter hinged to said flat plate member normally disposed to cover the record on the record strip and movable with said flat plate member to reveal the printed record made prior to the paper feeding operation. 30

3. In a time recorder, a continuous record strip, type wheels and a movable platen for printing a record on said strip, an actuating arm for operating said platen to effect a printing operation, and means for feeding said paper strip including a paper gripping device, paper guides for said paper strip, a member for sliding said paper gripping device back and forth to feed the paper strip between said guides, a member operable by said actuating arm, means including 40 a normally tensioned spring for effecting a mechanical connection between said members, said resilient means being further tensioned by the second-named member upon stoppage of the first-named member by paper jammed in said 45 guides. 50
